UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

CIRCUIT-BREAKER.

1,188,576.

Specification of Letters Patent. Patented June 27, 1916.

Original application filed January 13, 1905, Serial No. 240,866. Divided and this application filed July 1, 1910. Serial No. 569,870.

To all whom it may concern:

Be it known that I, PERCY H. THOMAS, a citizen of the United States, and resident of Montclair, county of Essex, State of New Jersey, have invented certain new and useful Improvements in Circuit-Breakers, of which the following is a specification.

A common mode of overcoming the initial resistance of a mercury vapor apparatus is that of connecting a reactance device in series with the apparatus, placing a shunt circuit across the mains between the vapor apparatus and the reactance device and then causing a quick rupture of the shunt circuit by means of a quick-break switch. A form of quick-break switch which is often used in this connection is one in which the contacts are made and broken under oil. The rupture of the circuit may take place either automatically through the action of the reactance device itself when the main circuit is closed, or through the action of some supplemental or auxiliary electro-magnetic apparatus designed to accomplish the rupture.

It is also common to operate the snap switch by hand.

In the present invention I provide, a substitute for the quick-break switch of the ordinary types, the said substitute being particularly adapted to cause an impulse of high potential to be impressed upon the circuit containing the mercury vapor device. It will be understood, however, that the present invention is not necessarily confined to such a use. It will be convenient, however, to describe the invention as applied in the manner indicated in the foregoing paragraph.

For convenience, I show in the present invention a mercury vapor apparatus having a positive electrode and a solid negative electrode. I have found by experiment that a solid negative electrode will not continue to carry current below a certain minimum limit, which limit is considerably higher than the limit at which a liquid negative electrode would act as a current carrier. That is to say, when a separation of the elec-

trodes takes place in an apparatus having a solid negative electrode, a positive rupture of the circuit is much more certain and reliable than in the case where a liquid negative electrode is used. It will be noted that there will ordinarily be a certain variable period of duration of current flow in the vapor on the separation of the cathode and anode on account of the energy stored in the inductance, which is available in high voltage form to perform this function. In fact, it may be said to be the strenuous effort of this inductance to maintain this current flow under the adverse conditions of small current and solid cathode that furnishes the high potential kick. It should, perhaps, be said as a matter of information that on large current there is no difficulty operating with a solid cathode for considerable periods of time, provided the result does not impair the vacuum, although the latter condition has prevented any considerable development of steady operation with solid cathodes.

It is, of course, important that the rupture of the circuit in the apparatus designed to accomplish the purposes of the present invention should be quick and clean, without danger of a following over after the separation of the electrodes. Accordingly, a circuit-breaker of this class containing a solid negative electrode is of distinct advantage in securing a quick and certain rupture of the circuit, resulting, in the embodiment illustrated in the drawing, in a quick and efficient reactance in the form of a high potential impulse imparted to the translating devices in the line.

Figures 1 and 2 of the drawing represent diagrams of types of circuits suited to illustrate the advantages connected with the embodiment of the circuit breaking device herein described, Fig. 1 showing a non-automatic system and Fig. 2 an automatic system of circuits.

Referring to the first diagram, 1 and 2 are, respectively, the positive and negative mains of a distribution system. The main

circuit may be closed by means of a switch, 3. Between the mains is arranged a mercury vapor apparatus, 4, having a positive electrode, 5, which may be of iron or other solid conducting material and a negative electrode, 6, of mercury. In series with the apparatus 4 is a reactance device, 7, as shown. Between the reactance device 7 and the mercury vapor apparatus 4 I connect 10 the mains 1 and 2 by a shunt circuit, 8, which includes a circuit-rupturing device embodying the present invention. This device consists of a container, 9, having a positive electrode, 10, of mercury, and a negative electrode, 11, of some solid material, such as iron wire. The said solid electrode 11, is extended into the apparatus far enough to come into contact with the mercury, 10, when the apparatus is out of operation 15 and the main circuit open. The device 9 may be provided with trunnions, one of which is shown at 12, on which the device may be turned for making or breaking contact between the electrodes, 10 and 11. By 20 tilting the upper end of the device to the left, as shown in the diagram, the mercury will recede from the solid negative electrode and a rupture of the circuit will take place within the device. When the switch 3 is 25 originally closed the device 9 is assumed to be in a position in which contact exists between the electrodes 10 and 11. If now, the device 9 be tilted so as to break contact between the electrodes, it is found that when 30 the solid element is made the negative electrode of the apparatus, the current will be cut off sharply at a certain comparatively high limit whereby the production of an impulse of high potential in the reactance 35 8 is rendered certain and absolute. Such high impulse being transmitted to the vapor apparatus 4 will break down the initial negative electrode resistance therein and start the apparatus into operation.

40 Fig. 2 illustrates an automatic system of accomplishing the same results. In this system I provide the container 9 with a band, 13, of magnetic material, the said band being arranged in operative proximity to the core 14 of an electromagnet 15 located in a high resistance shunt circuit 16 derived from the main circuit. The said circuit may be provided with a special resistance 17 to give it the necessary degree of resistance, 45 or the resistance may reside in the coils of the magnet 15 itself.

The operation is clear, when it is understood that on the closure of the main switch 3, a part of the main current passes through 50 the inductance 7 and the circuit-breaking devices already described, while a small portion of the current passes through the magnet 15, such small portion being, however,

sufficient to energize the said magnet and tilt the circuit-breaking apparatus. 65

Instead of the band 13 being itself of magnetic material it may be provided with an attachment 18 which is magnetic and which in combination with the core 14 would act to cause a tilting of the circuit-breaker, as will be readily understood.

It will be understood that the device forming the immediate subject of the present application may be used in other combinations and for other purposes than those 75 set forth herein.

It has been found convenient to describe and illustrate the circuit-breaker as a mercury vapor apparatus having a solid negative electrode and a liquid positive electrode. 80 It will be understood, however, that the positive electrode may be either liquid or solid, as found desirable. Should the positive electrode be a liquid, and should mercury be the liquid employed, I prefer that the 85 negative electrode should be made of a solid material not easily amalgamable with the mercury. Such a material might be iridium or some form of carbon, for example.

As indicated in the last paragraph, one 90 object is to use for the two coöperating electrodes materials which do not cause any deterioration one of the other by reason of the use thereof in a circuit-breaker of this general character.

This application is a division of my application Serial Number 240,866, filed January 13th, 1905.

I claim as my invention:

1. A quick-break switch for producing a 100 rise in potential comprising an evacuated vessel, and a liquid positive and a negative electrode therein, the negative electrode being of material in solid form.

2. A quick-break switch for producing a 105 rise of potential comprising an evacuated vessel, and a liquid positive and a negative electrode therein, the negative electrode being of solid material, thus tending to prevent free disintegration.

3. A quick-break switch for producing a rise of potential comprising an evacuated vessel, and a mercury positive and a negative electrode therein, the negative electrode being of material unable to amalgamate 115 with mercury.

4. A high potential kick switch, comprising an exhausted container, a liquid anode therein, and means for establishing a current flow from said anode into the vapor 120 space surrounding the anode and means for interrupting the current flow thus established, said means consisting of a cathode of solid material coöperating with said anode.

5. A high potential kick switch, comprising an exhausted container, a mercury

anode therein, and means for establishing a current flow from said anode into the vapor space around said anode and means for interrupting the current flow thus established, said means consisting of a cathode of non-amalgamable material coöperating with said anode.

Signed at New York in the county of New York and State of New York this 28th day of June A. D. 1910.

PERCY H. THOMAS.
